**PILOT'S HEADSET HAVING RECEIVER
AND TRANSMITTER**

**Richard H. Sarber, Ukiah, Calif., assignor to Multitech
International Corporation, Oakland, Calif.**

Filed Jan. 13, 1972, Ser. No. 217,718

Term of patent 14 years

Int. Cl. D14—03
U.S. Cl. D26—14 H

FIG. 1

FIG. 4

FIG. 2

FIG. 3

FIG. 5

FIG. 1 is a perspective view of a pilot's headset having receiver and transmitter showing my new design.

FIG. 2 is an elevational view seen from the left of the earpieces.

FIG. 3 is a similar elevational view seen from the right of the earpieces.

FIG. 4 is a front elevational view of the left earpiece.

FIG. 5 is a bottom view of the left earpiece.

I claim:

The ornamental design for a pilot's headset having receiver and transmitter, substantially as shown.
